Des. 208,555
Patented Sept. 12, 1967

208,555

RADIATION MONITORING BADGE

Eric L. Geiger, Santa Fe, N. Mex., assignor to Eberline
Instrument Corporation, Santa Fe, N. Mex.

Filed Mar. 17, 1966, Ser. No. 1,507

Term of patent 14 years

(Cl. D29—2)

FIG. 1 is a perspective view taken from the top, front and one side of a radiation monitoring badge showing my new design;

FIG. 2 is a perspective view taken from the bottom, rear and side opposite that shown in FIG. 1;

FIG. 3 is a side elevational view thereof; and

FIG. 4 is a bottom plan view thereof.

I claim:

The ornamental design for a radiation monitoring badge, as shown.
